UNITED STATES PATENT OFFICE.

OTTO B. MEYERS, OF QUAKERTOWN, PENNSYLVANIA.

AUTOMATIC REED-SAVING DEVICE.

Application filed March 8, 1926. Serial No. 93,326.

The present invention relates to an automatic reed saving device for overcoming the well known difficulties in warping in the manufacture of raw silk. As is well known raw silk is of such a texture that it cuts most anything, in continually moving over the same spot. This is what happens at present with the reeds. The silk is drawn from the creel to the crossing reed, the creel being wider than reed forces the ends to be drawn through the reed at an angle. It is this angular moving that cuts the reed. When the reed is cut the operator has difficulty in separating the ends of the silk, and in so doing some of the ends are broken, even with the most skilled labor. This breakage means a loss of time to the operator. To replace the reed is quite expensive, especially since a reed is badly cut after making four or five warps. Loss of time and replacement naturally means less production and higher overhead expenses. The ends of the silk that are drawn through the worn indenture, furthermore, lose their original strength by being continuously scraped, yet while they may not tear in the process of warping, they will tear when put in the loom and put under the warp tension. These difficulties are overcome by the present invention. The gist of the invention lies in the provision of a moving glass bar which keeps the silk continuously on the move, very slowly, in fact barely visible to the eye but, nevertheless, the silk is not confined to one spot for wear. Thus I obtain the following features; first, the life of the reed is lengthened indefinitely; secondly, a better grade of work is produced by each operator; thirdly, less difficulty in operations are encountered after warping; fourthly, better and speedier production is obtained; and fifthly, a better quality of goods is produced.

Another very important object of the invention is that the attachment is exceedingly simple in its construction, strong and durable, efficient and reliable, not likely to easily become out of order, and otherwise well adapted to the purpose for which it is designed. With the above and numerous other objects in view as will appear as the description proceeds, the invention resides in certain novel features of construction, and in the combination and arrangement of parts as will be hereinafter more fully described and claimed.

In the drawings:

Figure 1 is a side elevation showing a portion of a warper with my attachment associated therewith.

Figure 2 is a front elevation of the attachment.

Figure 3 is a top plan view of one end of the attachment.

Figure 4 is a detail sectional view taken substantially on the line 4—4 of Figure 3.

Figure 5 is an enlarged detail section taken substantially on the line 5—5 of Figure 2.

Figure 6 is a sectional elevation of a modified form of the drive.

Figure 7 is a front elevation of one of the brackets.

Figure 8 is another side elevation thereof.

Figure 9 is an enlarged detail section taken substantially on the line 9—9 of Figure 2.

Figure 10 is a perspective view of one of the blocks supporting the glass bar.

In the drawings similar numerals of reference refer to similar parts throughout the several views.

Referring to the drawings in detail it will be seen that the numerals 1 denote two brackets that are secured on the reed frame 30 by screws 31 or other suitable fastening elements passing through slots 32 thus permitting vertical movement of the brackets. These brackets 1 are made of angle iron. The numeral 3 denotes a glass bar over which the silk slides in going through the cross reed. The numerals 2 denote brackets that are supported in brackets 1. The brackets 2 are also formed of angle iron. The numeral 4 denotes a rod which extends through openings 34 in brackets 1 and through similar openings in brackets 2. The brackets 2 are secured to the bar 4 by a brazed joint 35 and extend to rotate in the openings 34 of the brackets 1 thus allowing the brackets 2 to swing in respect to the brackets 1. The glass bar 3 is attached to the brackets 2 by means of wooden blocks 36 which fit into the angle iron brackets 2 and are held in place by screws or other fastening elements 37. One of the screws 37 holds a part 38 of a latch, the pivoted part 39 of which is on the adjacent bracket 1, as is clearly shown in Figures 1 and 2. This latch 38, 39, holds the glass bar assembly in upright position while in use. The numeral 14 denotes a connecting rod that moves the glass bar assembly by the rotation of a drive wheel 20.

100
105
110

This rod 14 is knuckled by rivet 13 and allows a side movement by a slot and pin connection 12. The upper end of the connecting rod 14 is provided with a bearing 5 that allows the glass bar assembly to be tilted in any position the machine may stop, said bearing 5 receiving the rod 4 which is prevented from moving longitudinally along the rod 4 by pins 40. The numeral 16 denotes an equalizing shaft connected to brackets 1 by connecting arms 6. This shaft has crank extensions 16' at its ends. Each connecting rod is fastened to its bracket 1 by a screw or like fastening element 9. The connecting rods 6 are fastened to the crank 16' at points 17 by cutting a slot into the ends of the shaft the size of the connecting rod and using a small screw or like fastening element for holding them in place. The shaft is mounted on the reed frame by means of bearings 15. The numerals 18 denote parts of the angle iron brackets 1 at their lower ends which form stops when the glass bar assembly is swung down to put in the silk cross.

Referring particularly to Figure 1 it will be seen that the numeral 41 denotes the silk as it is drawn from the creel to the drum 42. As this is done the glass bar moves up and down so that the wear of the silk on the reed is distributed over the whole surface or rather over the extent of travel of the glass bar in relation to the reed. This motion of the glass bar is imparted thereto in the following manner. In the modification illustrated in Figure 1 a warping carriage is shown at 24 on the supporting rollers 43 and 44 which roll on the heavy iron bars 45 and 46, respectively, extending across the front of the warper. To obtain power to run my device, the roller 43 is knurled. A shaft 23 holds rollers 43 and extends to the front of the carriage and is there supported by bearing brackets 26. The crank 20 is attached to the end of this shaft which, in turn, moves the glass bar assembly up and down through connecting rod 14 by the transverse motion of the carriage as will be readily understood.

My device is adapted to any warper and the embodiment just described has been illustrated in reference to the well known Sipp warping mills. In Figure 6, however, I have illustrated an embodiment which may be used with other warping mills wherein it will be noted that a bracket 26' similar to bracket 26 is provided but much longer than bracket 26 and has a pin wheel 47 journaled in the lower end thereof on a shaft 48 on which is fixed the wheel 20. This pin wheel 47 is adapted to engage to the floor or the like upon transverse movement of the carriage thereby causing the rotation of the drive wheel 20 for operation of the glass bar as heretofore indicated.

It is thought that the construction, operation, and advantages of this invention will now be clearly understood by those having a skilled knowledge of warping mills without a more detailed description thereof. The present embodiments of the invention have been disclosed in detail merely by way of example, since in actual practice they attain the features of advantage enumerated as desirable in the statement of the invention and in the above description. It will be apparent, however, that numerous changes in the details of construction, and in the combination and arrangement of parts may be resorted to without departing from the spirit or scope of the invention as hereinafter claimed or sacrificing any of its advantages.

Having thus described my invention, what I claim as new is:-

1. An attachment for the reed of a warper; wherein the warper includes a carriage having a pair of arms extending vertically therefrom, said carriage being movable transversely of the warper; said attachment comprising a pair of brackets slidably mounted in the arms for vertical reciprocation independent of the reed and longitudinally of its dents, means for reciprocating the brackets vertically, a rod extending between the lower ends of the brackets and journaled therein, a second pair of brackets having their lower ends on the rod to pivotally mount the second brackets in relation to the first brackets, said second bracket reciprocating in unison with the first brackets, a bar extending between the second brackets.

2. An attachment for the reed of a warper; wherein the warper includes a carriage having a pair of arms extending vertically therefrom, said carriage being movable transversely of the warper; comprising a pair of brackets, means for slidably mounting the brackets on the arms for vertical reciprocation in respect to the reed longitudinally of its dents, a rod extending between the lower ends of the brackets and journaled therein, a second pair of brackets having their lower ends on the rod to pivotally mount the second brackets in relation to the first brackets, said second bracket reciprocating in unison with the first brackets, a bar extending between the second brackets, a

shaft journaled on the arms and having crank extensions at its terminals, links engaged with the crank extensions and with the upper ends of the first pair of brackets, and means engaged with the first lower rod and actuated by the transverse movement of the carriage to impart reciprocatory motion to the brackets.

3. A reed saving attachment for warpers; wherein the warper includes among other elements, a carriage having members rising therefrom, said carriage being transversely

of the warper; comprising a pair of brackets, means for slidably mounting the brackets on the members for vertical reciprocation with respect to the reed and longitudinally of its dents, a bar, means for mounting the bar between the brackets, means for moving the brackets vertically, a shaft, means for

rotatably mounting the shaft on the members rising from the carriage, cranks of equal length extending from the shaft, and a pair of rods of equal length pivotally engaged with the brackets and with the cranks.

In testimony whereof I affix my signature.

OTTO B. MEYERS.
